US00D892746S

(12) **United States Design Patent** (10) **Patent No.:** **US D892,746 S**
(45) **Date of Patent:** **** Aug. 11, 2020**

(54) **WATERPROOF RECEPTACLE CONNECTOR**

(71) Applicant: **Advanced Connectek Inc.**, New Taipei (TW)

(72) Inventors: **Yu-Lun Tsai**, New Taipei (TW);
Pin-Yuan Hou, New Taipei (TW);
Hsien-Lung Huang, New Taipei (TW);
Hsu-Fen Wang, New Taipei (TW)

(73) Assignee: **Advanced Connectek Inc.**, New Taipei (TW)

(**) Term: **15 Years**

(21) Appl. No.: **29/669,739**

(22) Filed: **Nov. 10, 2018**

Related U.S. Application Data

(62) Division of application No. 29/645,504, filed on Apr. 26, 2018, now Pat. No. Des. 842,814, which is a division of application No. 29/581,702, filed on Oct. 21, 2016, now Pat. No. Des. 828,305.

(57) **CLAIM**

The ornamental design for a waterproof receptacle connector, as shown and described.

DESCRIPTION

FIG. 1 is a front, top, right perspective view of a waterproof receptacle connector, showing our new design;
FIG. 2 is a front, bottom, left perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken lines depict portions of the waterproof receptacle connector that form no part of the claimed design. The dot-dash broken lines define the boundaries of the claim.

1 Claim, 5 Drawing Sheets
